UNITED STATES PATENT OFFICE.

HENRY G. CORDLEY, OF GLEN RIDGE, NEW JERSEY.

WATER-COOLER.

1,054,677.

Specification of Letters Patent.

Patented Mar. 4, 1913.

Application filed December 11, 1909. Serial No. 532,693.

To all whom it may concern:

Be it known that I, HENRY G. CORDLEY, a citizen of the United States, residing at Glen Ridge, in the county of Essex, State of New Jersey, have invented certain new and useful Improvements in Water-Coolers, of which the following is a description, reference being had to the accompanying drawings, forming a part hereof.

10 My invention relates to water coolers and has for its object to provide a cooler for water and other potable liquids in which the liquid holding receptacle shall be so constructed and arranged that a portion 15 only of it shall be exposed to the direct cooling action of the cooling medium employed in the cooling chamber while the main portion of the liquid shall be outside the cooling chamber and in sight and may or may 20 not be separately cooled.

In coolers for drinking water and particularly in coolers for lemonade and other drinkables which are sold by the glass it is found desirable to have the liquid so displayed as to be readily seen by the purchaser. Such arrangement is common in the so called inverted bottle water coolers which are in general use and in which a bottle or demijohn containing the main supply of liquid 25 is inverted over the open mouth of a liquid receptacle which is placed within a tank adapted to contain ice about this liquid receptacle for cooling it. This well known inverted bottle water cooler has the advantage of permitting the use of water or other liquid in original packages but has the disadvantage that a full package of liquid cannot be supplied until the package in use is exhausted, and has the further disadvantage of not cooling the reserve supply.

In vending lemonade, orangeade and like drinkables it is desirable at the beginning of the day when the ice tank is first filled, to have a full supply of liquid which is not possible with the inverted bottle cooler if at the close of the previous day the package in position on the cooler has been left partly full. It is also desirable to cool the reserve supply so that in case the liquid is 50 drawn off from the delivery faucet so rapidly as to exhaust the supply contained in the receptacle which is directly subjected to the cooling action of the ice in the ice tank, the liquid thereafter drawn will be cool. 55 This cooling of the reserve supply is very important where the liquid to be dispensed

is milk, butter milk, iced tea, iced coffee or other liquid which would sour or become spoiled if not kept constantly cooled.

By the device of my present invention all 60 of the display feature of the inverted bottle cooler is secured as well as other features such as the cooling of the reserve supply and the replenishing of the supply from time to time as may be desired.

65 The invention consists in the construction and combination of the elements hereinafter described and particularly pointed out in the claim.

Referring to the drawings; Figure 1 is a 70 vertical sectional view showing the cooling portion of the receptacle as a straight jar. Fig. 2 is a similar view showing the inner receptacle connected with the outlet faucet by a pipe coil. Fig. 3 is a horizontal sec- 75 tional view of the construction shown in Fig. 2.

In the drawings, 1 is an ice tank of any suitable material preferably of indurated fiber, having a drainage faucet 2 and cover 80 3, a portion 4 of the cover being removable to permit ice to be inserted.

5 is the combined reservoir and cooling receptacle comprising the inner cooling portion 6 and the outer display or reservoir 85 portion 7. The combined reservoir and cooling receptacle may be made in one piece throughout as shown in Figs. 1 and 3 and when so made is preferably made of glass though for some purposes it may be of porcelain or earthenware. The cooling receptacle portion 6 extends downward into the ice tank and preferably rests upon the bottom of the tank. Near its lower end it is provided with an opening in which is secured the inner end of the tube 8 of a faucet 9 which extends through the outer wall of the ice tank. The display or reservoir portion 7 is wholly outside the ice tank and is of larger diameter than the cooling receptacle portion 6 to which however it is united integrally. The inner cooling portion 6 may be a straight cylindrical jar as shown in Figs. 1 and 2 of the same diameter from the bottom to the point at which it joins the display or reservoir portion 7, or it may be made with a contracted neck at the point at which it joins this display or reservoir portion. If desired the tube connecting the cooling receptacle with the faucet 9 may be 105 of such length as to be coiled about the inner receptacle as shown in Figs. 2 and 3 so as

to afford a large surface for the cooling action of the ice. The display or reservoir portion 7 is preferably formed to resemble an inverted bottle or demijohn and is provided at its outer end with a removable cover 10. The reserve supply contained in the display or reservoir portion 7 may be cooled if desired by ice placed directly in the liquid, this being sometimes preferred when pure ice is obtainable, or may be cooled by placing therein a jar or receptacle 11 containing ice. This ice jar 11 is preferably of glass and may be supported in any convenient way so as to rest upon the inside 15 of the shoulders of the display or reservoir portion 7 as shown in Fig. 1.

The reservoir and cooling receptacle may be made of any desired size or shape. The cover of the ice tank should be so fitted 20 about the upper end of the inner cooling portion as to firmly support it against lateral displacement.

The tube 8 is made to be readily detached from the inner cooling receptacle 6 so as to 25 permit of thorough cleaning of the receptacle and of the tube.

It will be readily seen that liquid may be supplied in any quantity desired through the upper end of the display or reservoir 30 portion 7 after the cover 10 is removed.

The device has the advantage of attrac-

tively displaying the liquid and at the same time permitting additional liquid to be supplied as desired and the device is capable of being thoroughly cleansed with very little trouble.

Having thus described my invention, what I claim and desire to secure by Letters Patent of the United States is:—

In a cooler for liquids, the combination 40 of an outer receptacle adapted to contain a cooling medium, an inner receptacle adapted to contain liquid and having its upper portion above the top of the outer receptacle and of relatively large cross-sectional area 45 and its lower portion of relatively small cross-sectional area and formed integrally with the upper portion, closed at its lower end and extending downward through the top of the outer receptacle and having its 50 lower closed end resting on the bottom of the outer receptacle, a draw-off faucet exterior of the outer receptacle and a connection leading from the lower end of the lower portion of the liquid receptacle to the faucet. 55

This specification signed and witnessed this 22d day of September, A. D. 1909.

HENRY G. CORDLEY.
